DUST SEPARATOR

Charles Henry Wood Cheltnam, Brockley,
London, EnglandApplication June 24, 1936, Serial No. 86,978
In Great Britain June 27, 1935

7 Claims. (Cl. 183—80)

This invention relates to centrifugal dust separators of the kind comprising a separating chamber of approximately circular cross-section (i. e., of circular or scroll shaped cross-section) into which dust laden gas (hereinafter referred to as air) is propelled tangentially through a rectangular inlet passage extending substantially the full length of the chamber and from which the major portion of the air, more or less dust 5 free, passes either tangentially through an air port in the side of or axially into an open end in a central discharge pipe, and from which the minor portion of the air, which contains most of the dust, may be shunted to a comparatively 10 small cyclonic separator and precipitator. Separators of this kind are employed where large volumes of air or gas are to have only the coarse dust particles removed and have a high volumetric efficiency. In some cases, the central discharge pipe for the cleaned gas may be a chimney 15 or smoke stack.

It can be demonstrated by experiment with smoky gases that when a fluid passes round a bend in a duct of square or rectangular section, 20 two vortices are formed, the cross-sectional area of the duct being divided equally between them. The direction of the vortical motion is approximately at right angles to the main stream, and the direction of rotation is such that the flow of 25 the fluid adjacent to the flat sides of the bend is from the outer to the inner curved surface of the bend. If the bend is extended through an angle of 360 degrees so as to form a hollow circular prism comprising an inner and an outer 30 cylinder and two annular ends, assuming that the motion of the main stream is maintained, the two vortices become two vortex-rings rotating in opposite directions in any longitudinal section and "gearing" together at their adjacent 35 surfaces. The reason for these phenomena is the pressure gradient within the vessel, the pressure being greatest adjacent the outer wall; the viscosity of the fluid acting in such a way that a flow of fluid from a region of high to a region 40 of low pressure takes place adjacent to the surface of each of the two ends of the vessel. The matter is more fully explained in an article entitled "Experiments on Streamline Motion in Curved Pipes" by Prof. John Eustice in the "Proceedings of The Royal Society of London". A. 45 Vol. 85 (1911) on page 119, and also in an article entitled "Note on the Motion of Fluid in a Curved Pipe" by W. R. Dean, M. A. in the Philosophical Magazine, Vol. 4. (July—December 1927) on 50 page 208.

In separators of the kind specified, the main ingoing stream of dust laden gas is divided into two vortex rings, in the manner above described. In the case where the cleaned gas passes tangentially through a port in the side of the discharge 55

pipe each of the vortex rings evacuates itself independently of the other into the said pipe, each half of the gas passing through one vortex ring only; while in the case where the cleaned gas passes axially into an open ended eduction pipe 5 about half of the gas will pass through the vortex ring adjacent that end of the vessel in which is situated the said pipe and the whole of the gas will pass through at least a part of the other vortex ring, the first mentioned ring evacuating 10 into the second which evacuates the whole.

In separators of the kind specified, it has previously been proposed to shunt the concentrated dust laden air from the separating chamber either through a longitudinal dust port in the side wall or through radial dust ports in the end walls, said dust ports being situated some distance round the separating chamber from the inlet. In these previously proposed arrangements, owing to the relatively high velocity of 15 the secondary motions at the periphery of the vortex rings, compared with the primary motion, in all parts except in a portion of the first quadrant of the separator, a large portion of the finer dust cannot be caught in longitudinal or radial 20 dust ports and is swept into the central discharge pipe and some of the coarser dust cannot reach the said dust ports, and the separation efficiency of the apparatus is thereby reduced. The present invention is directed towards 25 increasing the separation efficiency, whilst retaining the high volumetric efficiency of this kind of separator.

In a separator of the kind specified, according to the present invention, a circumferential 30 dust port is provided at one or each end of the separating chamber and extends around at least a part of the circumference from a point near enough to the inlet to ensure that the dust is swept through the dust port or ports by the 35 secondary motions before it can be swept into the central discharge pipe. By "circumferential dust port" is meant a dust port the circumferential dimension of which is substantially greater than the other dimension.

Preferably the said port is formed in the end wall adjacent the periphery thereof and extends over at least half the circumference.

The air and dust passing through the dust port or ports may be shunted to a secondary 50 separating chamber and a suction fan arranged to draw air through the primary or both separating chambers and the said discharge pipe provided with adjustable dampers for adjusting the proportion of air shunted to the secondary 55 separating chamber the object being to maintain the overall separation efficiency, if and when the total volume of air to be cleaned is reduced, by compelling a greater proportion of the air to be shunted with the dust.

60

When a suction fan is used for drawing the air into the primary separating chamber anti-whirl vanes may be arranged to convert the whirling motion of the air to an axial motion prior to its entry into the fan.

The invention will now be described, by way of example, with reference to the accompanying drawings. Fig. 1 shows one form of the dust separator in side elevation and partly in section on the line I—I of Fig. 2, Fig. 2 is a section on the line II—II of Fig. 1 with lower part of scroll chamber broken away, Fig. 3 is a top or plan view, Fig. 4 shows a modified form of separator in side elevation partially broken away and shown in section; Fig. 5 is a section on the line V—V of Fig. 4 and Fig. 6 is a top or plan view of Fig. 4. Certain parts which are hidden from view are shown in broken line.

With reference to Figs. 1, 2 and 3, a primary separating chamber 1 of scroll shaped cross-section is provided with a rectangular tangential inlet passage 2 extending the whole length of the chamber. A circular discharge pipe 4 having an open end 5 extends axially into the chamber 1 through the end plate 3. The opposite end plate 6 is formed with a dust port consisting of a circumferential slot 7 extending from a point adjacent the inlet 2 over the major portion of the circumference.

A number of anti-whirl vanes 8 are arranged in the open end 5 of the pipe 4. Further within the pipe are arranged a pair of balanced dampers 9 mounted on spindles 10. These spindles extend through the side of the pipe 4 to enable the dampers to be operated from without to vary the size of the air passage through the pipe. The pipe 4 leads into the casing 11 of a suction fan.

The dust together with a small quantity of air is shunted from the primary separating chamber into a secondary separating chamber 12. This chamber 12 has a dirty air inlet 13, a clean air outlet 14 and a dust outlet 15 and constitutes a separate small cyclonic separator of the type described in British patent specification No. 406,036. The dust outlet 15 leads into a dust hopper 16. A duct 17 connects the dust port 7 to the inlet 13. A duct 18 connects the outlet 14 to the pipe 4 by means of the surrounding chamber 21.

In operation the suction fan in the casing 11 draws air through the pipe 4 and so draws the dust laden air into the chamber 1 through the tangential inlet passage 2. Owing to the tangential entry of the dust laden air, it is given a primary motion around the chamber 1. In addition to this primary motion a secondary motion is set up and results in the formation of two vortex rings in the manner described above. The dust moves to the wall of the separating chamber 12 under the influence of its superior centrifugal force and it will be seen that the slot 7 is situated so that the secondary motion assists in sweeping the dust on or near the wall through the slot 7. As the velocities imparted to the dust particles by the secondary motion is far greater than that imparted by the primary motion, the positioning of the slot in this manner leads to greater efficiency than in the case of a longitudinal dust port extending along the side of the chamber and through which the dust particles are directed almost entirely by the primary motion because in the latter case some of the dust will be carried centripetally onto the end wall and into the clean air outlet before it can pass sufficiently round the separating chamber to reach the lon-

gitudinal dust port. The secondary motion serves also to direct the air, after it has been freed of at any rate the major portion of its dust, into the open end 5 of the pipe 4, whence it is drawn by the fan and discharged into a chimney or other outlet. As this air enters the pipe 4 its whirling motion is converted by the vanes 8, so that the flow of air into the fan is almost wholly axial and the efficiency of the fan is thereby increased. In addition to drawing air from the chamber 1, the fan also serves to draw air through the duct 18 and hence draws the dust which passes through the port 7, together with a small portion of air, through the duct 17 into the secondary separating chamber 12. Here the air is freed of its dust, which falls through the outlet 15 into the hopper 16, and the clean air drawn through the duct 18 into the pipe 4, whence it is delivered to the chimney or other outlet along with the clear air from the chamber 1.

The proportion of air which is shunted into the secondary separating chamber may be adjusted by means of the dampers 9. By closing the dampers 9, the resistance through the primary separator is increased and thus more air is caused to flow through the secondary separator and vice versa.

It will be seen that the vanes 8 do not extend to the middle of the pipe 4. This is because there is a natural inert core passing axially through the centre of the chamber.

In the modified construction shown in Figs. 4, 5 and 6, similar reference numerals are used to denote parts corresponding to those in Figs. 1, 2 and 3. In this construction the discharge pipe 4 is not open ended, but extends through the chamber 1 from end to end, and is provided in its side with a rectangular port 19. This port is situated so that air entering through the passage 2 can only reach the port after passing most of the way round the chamber.

The adjustable dampers 9 are now fitted in this rectangular port. A further difference is that a circumferential dust port 7 is formed in the end wall 3 as well as in the end wall 6, the two ports being connected to the duct 17 by two separate ducts 20. In this case each dust port 7 extends over approximately half the circumference from a point removed from the inlet by about one quadrant.

In operation dust is discharged from the chamber 1 through both dust ports 7. Since the air cannot reach the port 19 until it has passed through at least two quadrants, the beginning of the ports 7 can be further removed from the inlet than in the first construction. Consequently the dust particles have become more accumulated on the wall of the separating chamber and the secondary motions have reached a greater velocity by the time they reach the dust port, than they do in the first construction. The clean air is directed into the port 19 by the primary motion. Apart from these differences the operation is similar to that of the first construction.

I claim:—

1. A centrifugal dust separator comprising a separating chamber of approximately circular cross-section, a dirty gas inlet passage of rectangular cross-section leading tangentially into the side of said chamber and extending substantially the full length thereof, a clean gas discharge pipe extending axially through said chamber from end to end, said pipe being provided in its side with a clean gas discharge port at a

- point remote in the direction of gas flow from that at which said inlet passage enters said chamber, and each end of said chamber being provided with a circumferential dust port adjacent the periphery and extending around at least a part of the circumference thereof from a point near that at which said inlet passage enters said chamber, and means for causing the dirty gas to pass through said inlet passage into said chamber.
2. A centrifugal dust separator comprising a primary separating chamber of approximately circular cross-section, a dirty gas inlet passage of rectangular cross-section leading tangentially into the side of said chamber and extending substantially the full length thereof, a clean gas discharge pipe extending axially within said chamber, at least one end of said chamber being provided with a circumferential dust port adjacent the periphery of said end and extending around at least a part of the circumference thereof from a point near that at which said inlet passage enters said chamber, a secondary separating chamber having a dirty gas inlet, a clean gas outlet and a dust outlet and constituting a separate small cyclonic separator, a duct connecting said dust port to the dirty gas inlet of said secondary separating chamber, a duct connecting the clean gas outlet of said secondary separating chamber to said clean gas discharge pipe of the primary separating chamber, and a suction fan to the inlet side of which said clean gas discharge pipe is connected, said fan serving to draw gas through both separating chambers.
3. A centrifugal dust separator comprising a separating chamber of approximately circular cross-section, a dirty gas inlet passage of rectangular cross-section leading tangentially into the side of said chamber and extending substantially the full length thereof, a clean gas discharge pipe extending axially within said chamber, at least one end of said chamber being provided adjacent its periphery with a dust port of narrow radial width and extending circumferentially over at least half the peripheral circumference of said end from a point near where said inlet passage enters said chamber, and means for causing the dirty gas to enter through said inlet passage into said chamber and to discharge clean gas through said axial discharge pipe, said means causing discharge of separated dust and residual dirty gas through said dust port.
4. A centrifugal dust separator as claimed in claim 2 comprising in addition adjustable dampers in said clean gas discharge pipe, said dampers serving to adjust the proportion of gas shunted to said secondary separating chamber.
5. A centrifugal dust separator comprising a separating chamber of approximately circular cross-section, a dirty gas inlet passage of rectangular cross-section leading tangentially into the side of said chamber and extending substantially the full length thereof, a clean gas discharge pipe extending axially within said chamber, at least one end of said chamber being provided with a circumferential dust port adjacent the periphery of said end and extending around at least a part of the circumference thereof from a point near where said inlet passage enters said chamber, a suction fan attached to the discharge side of said clean gas discharge pipe, said fan serving to draw the dirty gas into the separating chamber through said dirty gas inlet passage and draw the separated clean gas through said clean gas discharge pipe, and vanes arranged within said clean gas discharge pipe for destroying whirling motion of the clean gas before it enters the suction fan.
6. A centrifugal dust separator comprising a separating chamber of approximately circular cross-section provided with end walls, an inlet passage for dust laden gas of rectangular cross-section leading tangentially into the side of said chamber and extending substantially from one end wall to the other, a discharge pipe for cleaned gas located axially within said chamber and extending through at least one of said end walls, pressure means for causing a current of dust laden gas to enter the chamber through said inlet passage and by deflection of the circular wall of said chamber follow a curved path between said discharge pipe and the inner periphery of the chamber and thereafter discharge as clean gas through said axial discharge pipe, the curved path of movement of the current of gas in following the inner periphery of the chamber being adapted to develop vortex rings in said current of gas in the space between said end walls, said vortex rings being effective to carry the dust radially outward and then substantially transversely of the inner periphery of said chamber and toward said end walls, and a radially narrow circular slot-like dust discharge opening extending substantially half the circumference in at least one of said end walls, one edge of said discharge opening being coincident with the inner periphery of said chamber, through which the dust carried by said vortex rings is ejected and a circumferentially disposed conduit covering said slot-like discharge opening.
7. A centrifugal dust separator comprising a separating chamber of approximately circular cross-section provided with end walls, an inlet passage for dust laden gas of rectangular cross-section leading tangentially into the side of said chamber and extending substantially from one end wall to the other, a discharge pipe located axially of said chamber and passing through one end wall thereof, the inner end of the pipe opening within the chamber and the outer end thereof being provided with suction means for causing a current of dust laden gas to enter the chamber through said inlet passage and by deflection of the circular wall of the chamber follow a curved path between said discharge pipe and the inner periphery of the chamber and thereafter discharge as clean gas through said axial discharge pipe, the curved path of movement of the current of gas in following the inner periphery of the chamber being adapted to develop vortex rings in said gas current in the space between said end walls, said vortex rings being effective to carry the dust radially outward and then substantially transversely of the inner periphery of said chamber and toward said end walls, a radially narrow circular slot-like dust discharge opening extending substantially half the circumference in the end wall of the chamber, said discharge opening having one edge coincident with the inner periphery of said chamber, through which the dust carried by said vortex rings is ejected and a circumferentially disposed conduit over and cooperating with piping connections from said dust discharge opening for utilizing said suction means for carrying away the dust discharged from said opening.

CHARLES HENRY WOOD CHELTNAM.
